UNITED STATES PATENT OFFICE

CLOICE B. HULL, OF CLEVELAND, OHIO

FLOTATION ATTACHMENT FOR AIRPLANES

Application filed December 31, 1926. Serial No. 158,258.

This invention relates to a flotation attachment designed primarily for use on airplanes of the type generally known as land planes and which are constructed for making landings on the ground. Frequently, during long flights, etc., however, such planes become disabled over bodies of water and, as they have no means for rendering them buoyant, they sink below the surface and endanger 10 the lives of the occupants.

It is an object of the present invention to provide an attachment for an airplane which includes normally collapsed floats having means whereby they can be quickly inflated 15 by the generation of a gas, the said floats being of such size as to support the airplane with the tail portion projecting above the surface of the water so that it will act as a refuge for the passengers until rescued.

20 A further object is to provide a normally collapsed float which, when in its normal position will in no way interfere with the flight or manipulation of the airplane.

25 A still further object is to provide a generator utilizing calcium carbide or other gas forming elements to which water can be supplied quickly so as to quickly generate the gas and thereby rapidly inflate the released or unconfined floats.

30 With the foregoing and other objects in view which will appear as the description proceeds, the invention resides in the combination and arrangement of parts and in the details of construction hereinafter described 35 and claimed, it being understood that changes in the precise embodiment of the structure herein disclosed may be made within the scope of what is claimed, without departing from the spirit of the invention.

40 In the accompanying drawings, the preferred form of the invention has been shown.

In said drawings,

45 Figure 1 is a side elevation of an airplane equipped with a flotation device such as constitutes the present invention.

Figure 2 is a top plan view thereof, the two flotation devices being shown inflated.

50 Figure 3 is an enlarged vertical transverse section through one of the inflated flotation devices and a portion of the fuselage, the

generating apparatus being shown in elevation.

Figure 4 is an enlarged transverse section through the collapsed and retained float prior to release and inflation. 55

Figure 5 is a vertical section through the generator.

Figure 6 is a horizontal section therethrough.

Referring to the figures by characters of reference 1 designates the fuselage of an airplane and to each side thereof is secured an elongated casing 2 formed of a strong net. This net can be attached to the side of the fuselage in any manner desired and extended longitudinally thereof, the said net housing an elongated collapsible float 3 formed of rubberized fabric which, when inflated, will fit snugly against the net-like casing 2 and be reinforced thereby. Normally the float 3 is collapsed within the net, the net is folded thereover, and a retaining sheet 4 of heavy fabric or the like is arranged to completely cover the collapsed portion, this covering sheet being detachably fastened to the side of the fuselage by a rip cord 5 mounted in any manner desired and adapted to be operated from the cock pit. In the structure illustrated apertured lugs 6 are extended outwardly from the fuselage through eyes within the covering sheet 4 and the rip cord is extended through these lugs so as to retain the covering sheet thereon. Obviously by withdrawing the cord from the lugs the sheet 4 is released and the net casing and the inflatable member 3 can thus be distended. 70

When the parts are collapsed and covered, however, they do not offer any interference to the manipulation and flight of the machine. Of course, instead of having these parts mounted on the outer surface of the fuselage as shown, however, suitable recesses could be provided in the fuselage to receive them when collapsed. Such an arrangement is so obvious that it is not deemed necessary to show or describe the same in detail. 80

The means provided for inflating the attachment includes a generator one form of which has been illustrated. This generator includes a casing 7 adapted to be partly filled 85

with calcium carbide or other gas forming element, there being upstanding water distributing tubes 8 on the bottom of the casing adapted to be surrounded by the lumps of calcium carbide or other gas forming element. These tubes have small apertures 9 through which the water can escape and the casing is provided, adjacent its upper end, with an outlet slot 10 opening into an extension 11. This extension has a tubular outlet 12 from which tubes 13 are extended to the respective inflatable members 3. The generator casing has a removable cover 14 adapted to be held firmly in place by bolts 15 engaging ears 16 extending from the casing. Opening through this cover are nozzles 17 the outlets of which are directly above the respective tubes 8. These nozzles are all in communication with a water pipe 18 extending to the bottom portion of a water tank 19 located above the generator. A valve 20 may be provided in the pipe 18 for controlling the flow of water to the generator casing. An equalizing tube 21 opens into the top of the water tank 19 and into the top of the generator therebelow. A check valve 22 can be used to prevent water in the water chamber from entering the carbide chamber. Thus pressures within the water tank and generator are maintained the same. In practice the flotation attachments are held collapsed and housed as already explained while the generator casing 7 is charged with fresh calcium carbide or other gas forming element. Tank 19 is filled with water or other suitable gas forming means and valve 20 is of course closed. Should the airplane make a forced landing on the surface of a body of water the aviator or other person in the machine pulls the rip cords 5 and opens valve 20. The contents of the tank 19 will thus be directed into the tubes 8 and gas will be properly generated. This gas will escape through the outlet 10 and extension 11 to the tubes 13 and thence to the inflatable members 3. These will promptly expand or be distended by the gas delivered thereto until its maximum distension has been reached at which time each of the inflatable members 3 will be fitted snugly within the net embracing the same. Consequently when the airplane strikes the body of water the flotation devices will serve to hold the tail portion of the airplane extended upwardly so that it can provide a refuge for the passengers until rescued. If the flotation devices should not be fully distended when the airplane strikes the water, the gas will continue to generate after the airplane sinks and thereafter the entire structure will be brought to the surface.

The generator can be provided with a suitable pressure relief valve as shown at 23.

What is claimed is:

The combination with an airplane structure, including a fuselage, of an attachment

for holding the structure on the surface of a body of water, said attachment including a collapsible gas container, means for attaching said container to the airplane structure, at a point below the top thereof, means normally flat against the side of the fuselage and offering minimum wind resistance for holding the containers collapsed, said means being quickly released to permit expansion of the containers, and means for supplying gas to the collapsible container to expand it when released.

In testimony that I claim the foregoing as my own, I have hereto affixed my signature.

CLOICE B. HULL.
